United States Patent Office

Des. 178,660
Patented Sept. 4, 1956

178,660

FRONT DOOR PULL OR SIMILAR ARTICLE

Carl C. Hillgren, Newport Beach, Calif.

Application September 23, 1955, Serial No. 38,065

Term of patent 14 years

(Cl. D10—8)

Fig. 1.

Fig. 2.

Fig. 3.

I claim:

The ornamental design for a front door pull or similar article, substantially as shown.
